CHARLES DOERING AND HENRY H. DOERING, OF CHICAGO, ILLINOIS, ASSIGNEES TO
DOERING MANUFACTURING COMPANY, OF CHICAGO, ILLINOIS, A CORPORATION
OF ILLINOIS.

LAMP FOR MOTOR VEHICLES.

Application filed August 22, 1923. Serial No. 658,788.

Our invention relates to lamps or spot-lights adapted to be secured beneath the body of the vehicle, either fore or aft, as for example to the drip-pan beneath the 5 motor so as to be disposed in a plane between the bottom of the body and the axle of the running gear in order that a proper lighting of the roadway and to a suitable extent may be obtained without, however, presenting the objectionable glare frequently encountered with lamps as heretofore arranged and mounted.

Another object of our invention is to provide a lamp whereby the extent of forward 15 projection of the light-rays may be controlled so that blinding or confusion of approaching pedestrians or drivers will not be possible, while at the same time permitting a lighting of the roadway to an extent sufficient to enable proper and safe driving.

A further object of the invention is to provide a lamp provided with means whereby a proper focusing or adjustment of the lamp relative to the reflector and the lens 25 of the lamp may be effected and the adjusted position or regulation of the bulb of the lamp maintained; such adjustment being accomplished without a dismantling or need for especial implements or a screw-driver.

The various objects and advantages of our 30 invention, as well as the advantages inherent in the construction, will all be more readily comprehended from the detailed description of the accompanying drawings, wherein:—

Figure 1 is a partial side elevation and 35 sectional view of the front end of a motor driven vehicle with portions broken away to illustrate the application of our lamp.

Figure 2 is a vertical sectional view of 40 our improved lamp disclosed in Figure 1.

Figure 3 is a plan view of our improved 45 lamp with portions broken away.

Figure 4 is a detail sectional view taken 50 on the line 4—4 of Figure 2 looking in the direction of the arrows.

Figure 5 is a side elevation of a modified 55 form of our invention.

Figure 6 is a vertical sectional view taken 60 on the line 6—6 of Figure 5 looking in the direction of the arrows, with portions broken away.

Figure 7 is a sectional view taken on the line 7—7 of Figure 6 looking in the direction of the arrows.

The purpose of our invention is to provide a lamp with means whereby the lamp may be suitably secured to any point beneath the body of the vehicle and preferably in a horizontal plane above that of the axles of the vehicle so as to be suitably elevated, but not at an elevation where the light-rays will strike the eyes of a pedestrian or approaching driver.

As an exemplification of the invention, we show the lamp, in Figure 1, secured to a drip-pan 15 of the motor by means of suitable hangers 16 whose free ends are preferably bent at right angles and slotted, as indicated at 17 in Figure 3, adapted to be secured to the forward side of the drip-pan 70 by means of small bolts or otherwise. The lower ends of the hangers 16 are in turn pivotally connected, by means of bolts 18 which pass through the sides 19 at the forward end of a suitable splash-casing or shield 20; the bolts 18 being provided with suitable nuts whereby to effect a clamping relation between the hangers or arms 16 and the splash-casing or shield 20 and the proper angularity or adjusted position of the shield 80 maintained.

The shield 20 preferably consists of suitable sheet metal having the lower horizontally disposed portion 21 provided with the upwardly bent side flanges 19 and a vertical 85 disposed forward side 22, which may be integral with portion 21, and which is also preferably provided with rearwardly disposed side flanges 23.

The upwardly disposed wall 22 of the 90 splash-casing 20 is provided with a suitable opening and the wall about the opening formed with a rearwardly curled flange 24 which is adapted to receive a portion of the split-ring or clamping member 25—which is 95 semi-circular in cross-section—as shown in Figure 1. The clamping ring 25 in turn is adapted to receive the rim or flange 26 and the perimeter of the lens 27 of a well known type of spot-light. The split ring or clamping member 25, when drawn together at its split ends, by means of a screw and nut as 100

is usual, not only is firmly held in the rearwardly curled flange 24 of the wall 22 of the splash-shield 20, but also firmly clamps the spotlight in place.

5 The shell or casing 28 of the spotlight is provided with the usual hub or stem portion 29 through which the lead line, indicated at 30, extends and which also receives the bulb-holding socket member which is 10 held in place by the usual hard rubber ferrule 31; the line or wire 30 leads to a suitable switch mounted on the dash of the vehicle.

The horizontally disposed portion 21 of 15 the splash-casing 20 is preferably of a length sufficient to extend slightly beyond the ferrule 31 in order to prevent the lamp being splashed with water or dirt when the automobile is being driven; the side flanges 19 20 and 23 also affording additional protection.

The top of the vertically disposed wall 22 of the splash-casing is shown provided with a suitable hood or deflector 32 having sides 33 apertured to receive a bolt 34 whose 25 threaded end at the opposite side of the shield is provided with suitable washers and butterfly nut as at 35 whereby to effect proper clamping relation; the upper end of the wall 22 of the splash-casing being shown 30 curled upon itself to provide a suitable channel for the bolt as shown at 36 in Figure 2; this curled portion of the casing also providing suitable rigidity to the upper part of the construction. As is apparent from 35 the construction as shown in Figure 2, the hood or deflector 32 is arranged to swing through the arc of a vertically disposed circle toward and away from the lens 27, which enables the light-rays to be 40 controlled or deflected.

With this construction it is also apparent that the lamp will be placed closer to the roadway and afford a proper lighting forward of the vehicle without, however, 45 permitting the light-rays to extend into a plane where they would strike the eyes of a pedestrian or driver of an approaching vehicle.

In order to permit a proper positioning 50 of the bulb of the lamp relative to the reflector so as to obtain a proper focus—necessitated by certain constructions or inaccuracies frequently encountered in bulbs—we provide the lower side of the hub or stem portion 29 with a lip or ridge 37, see Figure 4; and the hub or stem 29 at diametrically opposite points, namely on top and beneath and therefore through the lip 37—is provided with slots 38 and 39 transversely of the hub to receive the rectangularly formed spring clip or wire 40 which is formed so as to have the long sides thereof extend into the inner circumference of the hub or stem 29 to engage with the socket member 41 whose forward end re-

ceives the bulb of the lamp; while the rear end is preferably provided with the ferrule 31. The socket member 41 is preferably provided with a plurality of circumferentially arranged grooves slightly spaced 70 apart to receive the sides of the spring clip 40 and thereby effect proper holding relation to maintain the socket member 41 with its bulb in the adjusted position; the spring clip 40 and the grooves in the socket member 75 41 being such as to permit the socket member to be moved lengthwise of the hub 29 by exerting a pulling or pushing force on the ferrule 31.

In Figures 5 to 7, we illustrate a modified 80 form of the invention, wherein a different method of securing the lamp in place is disclosed and the spotlight, having the usual type of casing generally shown at 28, is provided with a special shield 42, preferably 85 cylindrical in form, with the rear end, flared or flanged as at 43 so as to receive the rim of the casing 28 of the spotlight; the flared flange 43 at the bottom being provided with a lug as at 43^a adapted to fit rearward of the flange of the shell or casing 28 of the spotlight while the upper side of the shield 42 is provided with a spring clip 44 adapted to snap rearward of the flange of the shell or casing 28, as clearly shown in 90 Figures 5 and 7 thereby holding the shield in place on the forward perimeter of the spotlight.

The shield 42, at opposite sides, is shown provided with angular brackets 45 slotted 100 to receive the threaded ends of a transversely disposed rod or bracket member 46, held in place by means of suitable washers and nuts as at 47; while the rod or bracket member 46 in turn is provided with one or 105 more clips 48 shown in the nature of metallic loops bent about the rod with the ends arranged parallel and apertured to receive bolts or screws whereby the lamp may be secured at any convenient point beneath the vehicle, as for example to the drip-pan of the motor as previously described in connection with the construction shown in Figure 1. The clips 48 are of such nature that when the fastening screws 115 or bolts are completely screwed into place, the two portions or sides of the clip will be drawn into close relation and thereby firmly grip the rod 46 and hold the same against rotation in the clips.

In order to prevent any possibility of glare, we provide the shield 42 with a plurality of vanes or deflecting elements 49 preferably arranged transversely of the shield 42 in slight arcuate form as shown 125 in Figure 6 and extending from the forward end of the shield inward to a point slightly forward of the lens 27 of the spotlight. With this construction, the light-rays are divided up and deflected so as not to be 130

thrown upwardly to any considerable extent where they would encounter the eyes of pedestrians or an approaching driver; the vanes being preferably arranged in a somewhat sloping manner from a point near the upper side of the shield on one side thereof to a point somewhat beneath the longitudinal center on the opposite side.

The upwardly disposed rays reflected by the lower part of the reflector portion of the lamp housing, will enter between the vanes 49, which, however, will deflect the rays from their continuous upward sloping direction.

We have found in practice that materially better results are obtained by employing a bulb of a certain shade of blue glass, namely a daylight blue whereby a superior white light is produced which is more effective in properly lighting a dark or wet roadway; our improved lamp and bulb producing a better effect than is obtainable with the usual white lens and bulb.

We have shown certain constructions whereby the improved results are obtained and have described the same in terms employed merely as terms of description and not as terms of limitation, as structural modifications are possible and may be made without, however, departing from the spirit of our invention.

What we claim is:

1. In a lamp of the character described, the combination of a supporting bracket adapted to be suspended beneath the body of the motor driven vehicle, a shield secured to said bracket and having an opening therethrough, the wall of the shield about said opening being flanged to provide a socket,

means secured to said shield at the forward side thereof to control the light-rays, with a lamp-housing seatable in the socket about the opening in said shield, and means for removably clamping said lamp-housing in place.

2. In combination with a lamp having a shell or housing, a bracket for suspending the lamp in place, a supporting shield secured to the bracket and comprising a horizontally disposed bottom plate portion and an upwardly disposed plate portion integral with the forward edge of the bottom portion, the upwardly disposed portion being provided with a flanged opening to receive the forward edge of said lamp, and contractile means secured about the flanged opening whereby the shell of the lamp is removably clamped in the opening in said supporting shield.

3. In a lamp of the character described, the combination with a spot-light, of a supporting angular plate, one side whereof is disposed vertically and provided with an opening to receive the lens-holding perimeter of the spot-light, contractile means mounted about said opening whereby the spot-light is removably clamped in place, the other side of the plate being disposed horizontally beneath the spot-light to constitute a splash plate, a deflector member adjustably secured to the upper end of the angular plate, and a bracket adapted to be secured to the body of a motor driven vehicle for suspending the supporting plate in place.

CHARLES DOERING.
HENRY H. DOERING.
